RACE STARTING BARRIER

Harry Edward Good, Hawera, New Zealand

Application July 9, 1930, Serial No. 466,763
In New Zealand July 10, 1929

1. Claim. (Cl. 119—15.5)

This invention relates to the starting barriers, used principally in horse racing, of any of the known types in which a barrier tape is carried upon pillars or posts erected on the respective sides of the track, and is designed to be held in a lowered position to stretch across the track and then by the operation of the official starter, to be released and lifted clear of the track to permit the horses to pass beneath.

It is found difficult in the use of these barriers or starters, to obtain fair or satisfactory starts owing to the need of lining the horses up to the barriers and the natural restiveness of the horses, aided in many cases by the anxiety of their riders, keeping the horses moving about the stationary barrier. It is proposed by this invention to provide a method of starting under which the horses are marshalled against a barrier capable of travelling along the track, at a distance back from the starting point, and then causing the barrier to travel up the track towards the starting point, the horses moving with it, and the barrier then being raised at any desired point in such travel, to start the race. The horses aligned against the barrier are thus kept in motion, so that the liability to restiveness incidental to being kept motionless behind a stationary barrier is removed, and also the horses may be more satisfactorily aligned against the barrier. The starter then, when he has obtained this alignment, may release the barrier at any point in the distance it travels over.

The invention consists in mounting the barrier posts or pillars upon travelling carrier frames that are in turn mounted on rail tracks laid along the respective sides of the racing track for any desired distance so that the frames may run to and fro along such rails and carry the barrier along the track. It also consists in providing means upon such carrier frames whereby they may be driven to travel in the required direction and the driving controlled by the starter who will be carried on one of the frames which is made with provision for his accommodation. These driving means will be of such a nature as to provide for the two frames being synchronously operated and controlled.

The invention may be given effect to in a number of different ways and these may be such as to adapt it to varying circumstances. In the accompanying drawing a suitable manner is shown by which the invention may be carried out.

In such drawing:—

Figure 1 is a diagrammatic plan setting out the arrangement of the starter barrier apparatus

and the means whereby the barrier is caused to move along the track.

Figure 2 is an enlarged sectional view taken on line 2—2 of Fig. 1 showing a carrier frame for one end of the barrier, and its mounting.

Figure 3 is a side elevation of a carrier frame.

Figure 4 is a detailed sectional view taken on line 4—4 of Fig. 2.

The present invention is not concerned with the type of barrier employed, as it is adaptable for use with any of the existing and well known forms of barriers in which the barrier tape N extends from one side of the racing track to the other and is carried by arms O pivotally mounted upon vertical posts erected upon the respective sides of the track. These arms may be controlled by conventional means such as shown in U. S. Patent No. 587,285 to Harris and may be operated by springs Y. To release the barrier a release R operated by a pull cord R' is actuated, moving the bolt of the release out of the eye S. The springs Y then move the barrier up out of the path of the horses.

In this invention, however, the barrier carrying post A on each side of the track B, is mounted upon a suitably constructed carrier frame C and is provided with braces A'. Frame C runs to and fro upon a rail track D arranged to extend a distance parallel with that edge of the racing track and parallel with the rail track on the other side. These rail tracks are disposed to extend for any desired distance along the racing track length according to the starting points to be provided for.

The barrier thus is capable of travelling to and fro along the rail tracks by the travel of its carrier frames in a synchronized manner, to keep them opposite each other and the barrier extending transversely across the racing track. To ensure of this synchronized travel of the two frames C, they are connected together in any suitable manner, as for instance in the manner shown in Figure 1. In this the forward end of each frame C is connected to the rear end of the other frame, by means of a rope E attached to the forward end and carried forwardly alongside the rail track, to its forward end, and then returned round a guide pulley F and diagonally across the racing track to a guide pulley G positioned at the rear end of the rail track 50 round such pulley G and then forwardly for attachment to the rear of the other carrier frame. This provides that when either carrier frame is moved along its track, in either direction, a corresponding travel is imparted to the

other frame and the two are maintained in the same relative positions along the respective tracks. The ropes E are kept taut by any suitable tensioning device, and where they diagonally cross the race track, they are carried in tunnels 5 or piping T arranged beneath such surface. Consequently nothing extends across above the race track excepting the barrier tape itself.

The barrier carrier frames are caused to travel 10 to and fro along the track by any approved mechanism controlled by the starter official who will be accommodated upon one of the frames, as by providing such frame with a platform H upon which he may stand. This mechanism is 15 required to positively drive one of the frames only, the other frame being moved by the connections beforementioned, and such mechanism may be of any approved nature such as are well known in the art relating to transport driving means. 20 In Figure 1 the means indicated as being suitable for the purpose, comprise a cable J that is led from end to end alongside one of the rail tracks, and returns around suitable guide pulleys, and which is caused to continuously travel up and back again, by an electro-motor K driving it. 25 Mounted on the carrier platform H are two ordinary cable grip levers M, which are arranged to engage respectively with the cable as it travels in the two directions beneath the platform. As 30 shown in Figs. 2 and 4 of the drawing, the cable grips actuated by levers M are substantially identical to those shown in the patent to Brosnan, No. 750,162, of January 19, 1904. Levers M are preferably of the bell-crank type and are fulcrumed 35 by means of members 12 secured to the platform H. The short arm of the levers M is connected by a link 13 to a vertically movable block 10 which is attached to a grip member 9. The grip member 9 slides vertically on spaced rods 4. A 40 stationary grip member 6 is carried by the lower ends of the rods 4. To insure free movement of the cable J over the lower grip 6 when the upper grip 9 is in raised position, rollers 7 are provided.

Either grip may be actuated at will to grip the cable passing through it, while the other is free. Thus the carrier frame may be caused to travel in either direction, at the will of the starter official, by operating the requisite grip lever, and 5 may be stopped by freeing such grip.

The barrier itself will be actuated by the starter from his platform H so that as he is travelling along with the barrier and has the horses aligned, he may release the barrier. 10

I claim:—

In a starting barrier for a race track, a rail track extending along each side of the race track and parallel to the rail track on the other side, a carrier frame movably mounted on each rail track, vertical posts on the carrier frames for supporting the corresponding ends of a starting barrier tape, a pulley positioned at each end of the rail on both sides of the race track, a tunnel extending under the race track from a point adjacent one end of each rail to a point adjacent the opposite end of the rail on the other side of the race track, a rope connected to one end of one carrier frame, said rope passing over the pulley at the corresponding end of the rail through one of said tunnels, over the pulley at the opposite end of the other rail and being connected to the opposite end of the other carrier frame, a rope similarly connecting the other ends of the carrier frames and passing over the other pulleys and through the other tunnel whereby both carrier frames will move synchronously and corresponding distances in the same direction, a two-way hauling cable extending along one of the rails, means for causing the cable to travel up and down the track in two lines moving in respectively opposite directions, a platform on one of the carrier frames, means on the platform for locking its frame to either line of cable and for releasing it therefrom, and means on the vertical posts for raising the barrier tape at any point along the travel of the frames on their rails. 30 35 40
